UNITED STATES PATENT OFFICE.

WILLIAM H. FORD, OF LOWELL, MASSACHUSETTS.

APPARATUS FOR MAKING MOLDS FOR RINGS, &c.

SPECIFICATION forming part of Letters Patent No. 663,018, dated December 4, 1900.

Application filed March 10, 1900. Serial No. 8,121. (No model.)

To all whom it may concern:

Be it known that I, WILLIAM H. FORD, of Lowell, county of Middlesex, State of Massachusetts, have invented an Improvement in 5 Apparatus for Making Molds for Rings and Analogous Articles, of which the following description, in connection with the accompanying drawings, is a specification, like characters on the drawings representing like parts. 10 Prior to this invention attempts have been made to cast gold and other metallic rings in molds composed of moldable material stamped or worked to present a recess of a shape corresponding with the article to be 15 cast; but said attempts have resulted in failure, for the reason that a ring free from blow-holes could not be produced in such a mold, and, further, the surface of the cast ring has been so irregular and imperfect that it re- 20 quired in finishing the ring considerable of the metal had to be removed, the change of condition of the metal of the ring by the removal of its roughened surface so changing the size of the ring and so altering the weight 25 of the metal poured into the mold that a ring of a defined size and of a desired pennyweight could not be practically made. So, also, solid plain gold rings have been made by a drawing or swaging operation, a blank of suitable 30 shape being acted upon by a succession of dies to bring the blank into a shape in cross-section required for the production of the ring desired, such reduction of the blank re- 35 quiring several operations and each operation requiring a special machine having its own attendant.

Appreciating the desirability and great importance of being able to quickly form a solid ring from gold or other metal by casting, so 40 that a jeweler or other manufacturer may readily measure a finger and make for it a ring of the proper size and of the desired shape and style, I have devised an apparatus, to be hereinafter more fully described, by 45 which may be quickly fashioned a mold in friable material—such, for instance, as charcoal, soapstone, or pumice-stone—I prefer- 50 ably using charcoal, because the surface of the mold readily assumes a heat correspond- ing with the heat of the metal, thereby pre- venting the gold from cooling too freely in

the mold-space. Prolonging the cooling op- eration enables the air in the mold to escape therefrom through the metal before the lat- 55 ter sets sufficiently to form an obstacle to re- sist the passage of the air, the air of the mold escaping through the molten metal, the metal readily flowing to close any passage made through it by the air, thus obviating blow- 60 holes in the casting.

While I prefer charcoal for the mold, it will be understood that the apparatus to be herein described and claimed, broadly, may be used to cut a mold-cavity in any material. So this 65 invention is not intended to be limited in its use to the cutting of a mold in any friable material.

In casting a ring from gold, silver, or other precious metal I first cut or face one side of a piece of charcoal to present a smooth hori- 70 zontal face, and thereafter by a suitable tool or device I drill a centering-hole in the char- coal or other material, said centering-hole being exactly at right angles to the plane face of the material. The mold material hav- 75 ing been prepared, I put the mold material in operative relation to a revoluble tool-carrier, to be described, it carrying a suitable tool to cut a mold-groove about the centering-hole and having a central opening, and holding 80 the mold material properly centered with re- 85 lation to the tool-carrier I rotate the said cutter or the mold material, or both, to enable the tool to cut a circular cavity in the mold material concentric with the centering-hole 90 therein.

The mold material is shown as centered on a centering-pin occupying a position in aline- 90 ment with the longitudinal center of rotation of the tool-carrier, and the mold material guided by said pin is acted upon by the tool of the tool-carrier, said mold material grad- ually approaching a stop or arresting device, shown as carried by the tool-carrier, the mold material meeting said stop when the mold- 95 groove has been cut to the predetermined depth.

The mold-cutter has a suitable cutting-tool or blade which may be adjusted toward and from the center of rotation of the mold-cut- 100 ter to thereby provide for cutting a circular groove in the material of any desired diam-

ter, according to the size required for the ring, and said tool may also be adjusted longitudinally of the axis or center of the mold-cutter to thereby provide for making a groove of 5 the desired depth, the depth varying with the width of the ring to be produced.

To define accurately and quickly the size of the annular groove to be cut in the mold material that it may correspond exactly with 10 and fit the finger to which the ring is to be applied, I employ what I herein designate as "size-disks." Having determined the size or diameter of the ring to be made, I place a size-disk upon the centering-pin, it occupying 15 a position centrally with relation to the mold-cutter, and I then adjust the cutter toward and until it meets the periphery of said disk, and I then confine the cutter in such position, and thereafter I remove the size-disk, adjust 20 the tool longitudinally, so that it may act to cut a groove equal to one-half the width of the ring and clasp the tool in position. I use two similar pieces of material in the production of each mold, each piece containing one- 25 half of the mold-cavity, each cavity registering with the other when the centering-holes made in the material coincide, and each half of the material having a suitable runway cut from each annular groove or mold-cavity to 30 the edge of the material.

The tool or blade selected for use will be shaped upon that side most distant from the centering-pin to correspond with the exterior contour which it is desired shall be given to 35 the ring to be cast, the inner edge of said tool or its edge next the said centering-pin having the shape which it is desired to give to the interior of the ring.

From the foregoing it will be understood 40 that a person knowing the size and style or shape in cross-section desired for a ring to be cast and having a suitable tool to apply to the mold-cutter may readily and quickly adjust the tool, putting it into a position, and 45 cut a mold of the desired size and shape.

Figure 1 in side elevation represents one 50 form of mold-cutter for the formation of a mold-cavity in material in accordance with my invention, it showing a size-disk in position. Fig. 2 is a left-hand end elevation of the mold-cutter represented in Fig. 1, a size-disk being shown by dotted lines. Fig. 3 is a section in the line x^2 , Fig. 2, the material for one-half of the mold being in place, the 55 mold-cavity being shown as finished in the dotted-line position of the material. Fig. 3^a shows the tool *e* removed from the tool-holder. Fig. 4 shows the tool-holder removed, it containing the tool. Fig. 5 represents in face 60 view the material having formed in it one-half of the mold-cavity. Fig. 6 shows in section two such mold-halves brought together with the centering-holes in alinement for the reception of a suitable centering-pin. Fig. 65 7 represents a different form of tool or blade from that shown in Figs. 1 and 3. Fig. 8 shows a ring such as will be cast in the mold-

cavity cut by the tool represented in Fig. 3. Fig. 9 represents a ring such as may be cast in a mold-cavity cut by a tool such as represented in Fig. 7. Fig. 10 represents a section of the tool-holder in the dotted line x^2 . Fig. 11 represents one side of a piece of mold material faced to represent a plane surface and provided with a centering-hole.

Referring to the drawings, *b* represents a piece of mold material—for instance, charcoal—it being cut to present a smooth or plane face b^x , which is provided with a centering-hole *b'*, located exactly at right angles 80 or perpendicularly to the face b^x .

The mold-cutter *C* is herein represented as composed of a tool-carrier *c'*, bored preferably centrally at *c*. The tool-carrier may have at one end a projection *c²*, represented as 85 threaded, for the attachment thereto of a stem or end piece *c³*, also bored centrally at *c⁴* and provided, preferably, at its outer end with a bushing *c⁴*, of wood or of fiber, said bushing having a tapered hole to be fitted, when the 90 mold-cutter is to be rotated by power, on the end of a spindle (not shown) of a polishing-lathe. If desired, however, the operator may hold the tool-carrier in one hand and rotate the tool-carrier by hand. The tool-carrier is provided with a hole *a* parallel with the hole *c*, located at the center of rotation 95 of the tool-carrier, said hole *a* at one end of the carrier having an enlargement or cavity *a'*. The hole *a* receives the shank *a²* of the 100 tool-holder *a³*, having a working outer face *a⁴* to arrest the material *b* when the mold-groove *b²* has been cut to the required depth. The tool-holder *a³* has two passages *d* *d'*. The passage *d* is represented as extended 105 through the tool-holder parallel to the shank *a²*, said passage in the working position of the tool-holder being parallel to the longitudinal axis of rotation of the tool-carrier. The passage *d'* is shown as extended but part 110 way through the tool-holder. The tool-holder shown has two notches or seats 2 3, each of which is provided with a tapped hole to receive, respectively, two clamp-screws 4 5, the screw 5 being shown only in Fig. 2.

The tool (shown detached in Fig. 3^a) consists of a shank *e*, having a blade *e'*, shaped to cut a groove *b²*, presenting the outer side of its wall concaved and the inner side of its wall parallel to the longitudinal axis of the 120 tool-carrier, a groove of such shape enabling a ring to be cast having the contour represented in Fig. 8.

With a tool having a blade shaped as represented at *e²*, Fig. 7, a groove would be cut 125 having parallel sides which would enable a ring to be cast of the shape shown in Fig. 9.

The clamp-screw 4 acts against the shank and holds the tool *e* in its adjusted position, as will be described. The clamp-screw 5 130 when used will act against the shank of and hold a tool (not shown, but which will be put in the passage *d'*) when the mold-cutter herein shown is to be used to cut in mold mate-

rial a groove varying in depth or to cut a mold-groove as provided for in my application Serial No. 728,566, filed August 26, 1899.

To maintain the tool *e* in position temporarily when preparing for cutting a mold-groove, I have provided the shank *a*² of the tool-holder with a spiral spring *b*, the free ends of which press upon the shank of said tool and, acting frictionally, maintain it in position in which it may be slid. A centering-pin *h* enters loosely the central hole in the tool-carrier, said pin being herein represented as entering the shank *c*³ and having its end projected beyond the face of the tool-holder, the pin occupying this position when the tool-carrier is to be held in the hand of the operator and rotated by hand; but in case the operator should prefer or in case the tool-carrier is to be rotated by power, in which case the said shank is to be pushed upon the end of the tapered spindle of a polishing-lathe, then the centering-pin may be made to enter the central opening of the tool-carrier from the opposite direction, leaving the bushing *c*⁴ unobstructed.

The shank *a*² of the tool-holder may be held in its adjusted position in the tool-carrier by a clamping-screw *a*^x.

To make a ring of a given size, I first get the measure of the finger, using, preferably, size-rings in usual manner, and having ascertained the size of the finger I select and apply to the centering-pin *h* (see Fig. 1) a size-disk *g*, herein shown as double-ended, it being numbered at one end to correspond with the size-ring, said disk being shown in full lines in Fig. 1 and by dotted lines in Fig. 2. Having selected a sample ring of a shape in cross-section of the ring to be made, I select a tool having a blade of the proper shape to cut a groove of the shape necessary to cast a ring of the style represented by the sample ring, and I insert the shank of the tool in the passage *d* of the tool-holder loosely, and then to determine the width of the ring in accordance with the sample ring I lay on the face *a*⁴ of the tool-holder one side of said sample ring and adjust the tool longitudinally in said passage *d* until the point of the blade of the tool comes exactly opposite the center of the width of said ring sample, and I then fasten the tool in place by a clamp-screw *a*^x. Having confined the tool in proper position in the tool-holder, the clamp-screw *a*^x being at that time loose, I turn the tool-holder in the tool-carrier until the end of the blade contacts with that end of the size-disk next the tool-holder, such adjustment of the tool-holder putting the tool in exactly the proper position to cut in the mold material a groove corresponding exactly in diameter to the ring it is desired to produce of a definite finger-size and pennyweight, and I then turn the clamp-screw *a*^x and fix the tool-holder in its adjusted position.

By the foregoing adjustments I have determined both the diameter of the groove to be

cut and its depth, and the depth of the groove equals one-half the width of the ring to be cast, it being understood that I form one-half of the mold-space in a different piece of mold material.

The tool shown in Fig. 3^a cuts a groove for the production of the ring having a convexed exterior, as shown in Fig. 8; but the tool shown in Fig. 7 would make a flat band-ring, as shown in Fig. 9, it presenting right-angled edges with straight parallel exterior and interior.

By my invention I may cut a mold-groove of any desired shape, I having only to change the shape of the blade that it may cut a mold-groove of any desired cross-section, so that by my invention I may make rings of any desired shape in cross-section.

Having adjusted the tool to the requirements of the ring to be cast, both as to finger-size, shape in cross-section and pennyweight requirement, the size-disk *g* is removed from the centering-pin. I must now center the mold material with relation to the longitudinal center of the tool-carrier, and to do this I take the mold material and place the hole *b*' therein upon the centering-pin, thus alining said hole with the longitudinal center of the tool-carrier, so that as the blade of the tool acts in its orbital movement the groove cut will have as its center the hole *b*', previously made in the mold material, the cutting of the groove leaving a central core *b*⁴, defining the finger-size.

The mold material *b* (see full lines, Fig. 3) when applied to the centering-pin *h*, is supported thereby outside the face *a*⁴ of the tool-holder, and by engaging the mold material by one hand I press the mold material gently against the blade, and while the mold-cutter or the mold material or both are rotated I cut in the mold material a groove concentric with relation to the centering-hole *b*', the mold material being gradually made to approach the stop-face *a*⁴ of the tool-holder, the meeting of the material and said face determining the depth of the groove and stopping any further cutting action of the tool.

It will be noticed that the tool is mounted eccentrically upon the tool-holder, so that by the adjustment of said tool-holder the tool may be made to occupy a position more or less near the longitudinal center of rotation of the tool-carrier, it being thus possible to instantly provide for any required diameter of ring.

Each part of the mold-groove *b*² is provided with a suitable runway, as *m*, and the mold-grooves in the two mold-sections when face to face may be kept in alinement by inserting a suitable pin in the holes *b*'.

A cast ring taken from the mold-space, consisting of two grooves *b*² face to face, will be found to be malleable and to present smooth exterior and interior, requiring but little finishing, thus making it practical to cast a ring to finger-size and practically to any desired

pennyweight requirement, and it will be understood that the smoother the casting the less the material of the ring that need be removed for finishing, and consequently the 5 quicker the production of a ring to exact finger-size and pennyweight requirement, and, further, the cost of finishing a smooth ring-casting is much less and may be done with the expenditure of but little time.

10 The rings cast in the charcoal mold such as described will be found to be practically free from blow-holes and malleable. A mold of this character is made the subject of application Serial No. 6,150, filed February 23, 15 1900.

In Figs. 8 and 9 the rings shown have connected with them runners n , such runners representing gold which overflowed from the mold-space, and it will be noticed that these 20 runners are of small diameter, leaving when broken off but a small portion of the surface of the ring to be dressed to the level of the face of the ring.

This invention is not limited to the exact 25 construction shown for the tool-holder, nor to the exact construction for the tool-carrier, nor to the exact construction represented for centering in alinement the tool-carrier and the mold material.

30 I have herein spoken of my invention as applicable for making molds for casting rings; but it will be obvious that molds made by the apparatus herein described may be employed for casting any other articles than rings, and 35 the mold-cavities may be of any shape and extend throughout more or less of a circle.

To lessen the number of size-disks necessary and to also economize in their cost of production, I have made a double-size disk, it 40 presenting at its opposite ends different diameters, the diameter at one end representing a full-size, while the diameter at the opposite end represents a half-size, and in using this double-size disk I apply next the face a^4 of 45 the tool-holder that end of the size-disk containing the number defining the size of the ring to be made.

Having described my invention, what I 50 claim as new, and desire to secure by Letters Patent, is—

1. In a mold-cutter, a tool-carrier, a cutting tool supported thereby, and a centering-pin in co-operative relation with the tool-carrier and adapted to constitute a pivot or support 55 for the mold material to be cut.

2. In a mold-cutter, a tool-carrier, a cutting tool supported thereby and adjustable with relation thereto, and a centering-pin in co-operative relation with the tool-carrier and 60 adapted to constitute a pivot or support for the mold material to be cut.

3. In an apparatus of the class specified, a tool-carrier, centering means in co-operative relation therewith and adapted to constitute 65 a support for the mold material to be cut, a tool mounted for adjustment longitudinally of the axis of rotation of said tool-carrier, and

means to arrest the approach of the mold material toward said tool-carrier to stop the cutting operation when a groove of a predetermined depth has been cut.

4. In an apparatus of the class specified, a tool-carrier, a longitudinally-movable centering-pin guided by said tool-carrier and constituting a pivotal support for the mold material, a tool-holder, a cutting-tool mounted thereon and serving to cut a groove in the face of said material, and means for stopping the feed of the mold material when a groove of a predetermined depth has been formed 80 therein.

5. In an apparatus of the class specified, a tool-carrier, a centering-pin for the mold material movable longitudinally of the axis of the tool-carrier and constituting the sole support for said mold material, a tool-holder having its shank supported by the tool-carrier, said shank being in parallelism with said centering-pin, a tool adjustable longitudinally in said tool-holder, a device for holding the 90 tool in its adjusted position, and means for stopping the feed of the mold material when a groove of predetermined depth has been formed therein.

6. In an apparatus of the class specified, a 95 tool-carrier, means to serve as a stop for the mold material when provided with a groove of the required depth, a centering-pin occupying a position in the longitudinal center of the tool-carrier and constituting the sole support for the mold material, a cutting-tool sustained in said tool-carrier, means for adjusting said cutting-tool longitudinally and also toward and from said centering-pin, and means to hold said tool in its adjusted position.

7. In a mold-cutter, a tool-carrier provided with a central opening, a tool-holder, a tool carried thereby and eccentric thereto, and means to adjust said holder to place said tool at any desired distance from the center of rotation of the tool-carrier.

8. In a mold-cutter, a tool-carrier, a longitudinally-movable centering pin or device occupying a position in the longitudinal center of said tool-carrier, a size-disk applied to said centering pin or device and a tool or blade adjustable to meet the edge of said disk to define the interior diameter of the groove to be cut.

9. A size-disk having a central opening and presenting ends varying in diameter to thereby enable each disk to be used to indicate two diameters.

10. In a mold-cutter, a centering-pin, a cutter movable in a circle outside said centering-pin, and a double-ended size-disk.

11. In a mold-cutter, a tool-carrier, a tool, means connected to the carrier acting to temporarily hold said tool preparatory to adjustment, and a device to clamp said tool in adjusted position.

12. In a mold-cutter, a rotatable cutter-carrier, and a tool-holder mounted therein

and adapted to receive a cutting-tool, said holder being rotatable in said cutter-carrier about a center parallel with the center of rotation of said cutter-carrier to thereby enable 5 the tool in said holder to be put at any desired distance from the center of rotation of said cutter-carrier.

13. A tool-carrier having a longitudinal opening, a tool carried by said tool-carrier 10 and adapted to cut a mold-groove, a centering-pin to carry mold material and adapted

to enter and be slid in said opening while the tool is acting to cut the mold-groove in said material.

In testimony whereof I have signed my 15 name to this specification in the presence of two subscribing witnesses.
